UNITED STATES PATENT OFFICE.

RICHARD V. MCKAY, OF STEELTON, PENNSYLVANIA.

COOLING-PLATE FOR NODULIZING-KILNS.

1,222,646.

Specification of Letters Patent. Patented Apr. 17, 1917.

Application filed August 30, 1915. Serial No. 48,104.

To all whom it may concern:

Be it known that I, RICHARD V. MCKAY, a citizen of the United States, residing at Steelton, in the county of Dauphin and State of Pennsylvania, United States of America, have invented certain new and useful Improvements in Cooling-Plates for Nodulizing-Kilns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to nodulizing kilns, and has for its object the removal from such kilns of the accretions that form near their discharge ends in a ring.

It is well known that in nodulizing kilns there is formed, in the kiln, at the scorifying or fusing zone a ring of refractory material, which gradually increases in thickness and prejudicially affects the proper operation of the kiln.

Varicus devices have been used for removing these rings, such as a cooling section placed in the kiln walls at one or more points of the circumference of the kiln, so as to chill the ring of accretions and cause it to crack and fall off. The explosive force of steam has also been utilized for this purpose, by causing water to be supplied at points on the interior surface of the lining of the kiln and between said lining and ring of accretions, thereby generating steam between the lining and the ring of accretions, and causing said ring to be blown asunder.

As is well known, nodulizing kilns are long, cumbersome inclined furnaces mounted on rollers, the structure being such that the kiln does not rotate on a true axis, and when supplying water for the purposes above stated it was necessary to provide a stationary pipe at the center of one end of the kiln, so that as the kiln rotated there would be continuous communication between the supply pipe and the water circulating system rotating with the kiln and about such pipe as center. The objection to this central supply is that one end of the kiln, usually the delivery end, is obstructed by such a central water pipe and its connections across the end of the kiln, so that the manipulation of

the charge by implements is rendered troublesome or impossible. Another objection is that it is practically impossible to make a water-tight joint between the stationary supply pipe and the radial pipe supplying water to the cooling or exploding system, by reason of the non-axial rotation of the kiln. These difficulties have led me to experiment with other means and modes of cooling the kiln at one or more points, so as to crack the rings formed in the furnace, and thereby break the arch and allow them to fall down into the kiln.

I have discovered that steam will have a sufficient and proper cooling action to cause this breakage or cracking of the rings; and I have devised means for effecting this cooling action without the use of a central end supply pipe and radial feed pipe. The method of operation is that at each rotation of the kiln a quantity of water is taken up or collected by suitable devices on the exterior of the kiln and caused to pass into cooling sections or plates inserted in the kiln walls, and preferably, but not necessarily, made removable and exchangeable from the outside of the kiln, thus enabling a very rapid exchange of a new section or plate for one that has burned out, without requiring the removal and replacing of the kiln lining around the plate. This water is converted into steam that cools a segment of the accretion ring sufficiently to crack it, there being provided means for the continuous escape of steam from the plate or plates.

Referring to the drawings, in which like parts are similarly designated—

Figure 1 is a side elevation of the discharge end of a nodulizing kiln, showing my invention applied thereto.

Fig. 2 is a section on the line 2—2 of Fig. 3.

Fig. 3 is a bottom view of the cooling element or plate.

Fig. 4 is a longitudinal section thereof.

Fig. 5 is a transverse section of the dipper or bucket.

Fig. 6 illustrates a modified form of cooling plate arranged to be removed from the exterior of the kiln without disturbing the kiln lining.

Fig. 7 is an elevation of a kiln showing the bucket or dipper arranged near the upper or inlet end.

Fig. 8 is an end view, partly in section,

showing the arrangement of the dipper and tank.

The furnace or kiln shell 1 is provided at a suitable point along its length with rails 5 or rings 2 supported by rollers 3 held in bearings 4 on a suitable foundation 5, as is customary with nodulizing furnaces or kilns.

Inserted in the shell 1 at a point in the circumference thereof, and preferably at the zone where the ring is prone to form, I place one or more hollow cooling sections arranged longitudinally of the kiln.

These sections or plates are constructed as shown in Figs. 2, 3 and 4, and may be made of cast iron, but preferably of pressed steel, riveted and welded together to make them water and steam tight.

As shown in Figs. 2, 3 and 4, such a hollow cooling section consists of two parts, a body portion 7, riveted and welded to a curved plate 8 provided with rivet or bolt holes 9, by means of which the plate is secured to the furnace shell.

Each plate has two pipe nipples 10, one of which serves as an inlet and the other as an outlet. And secured to the furnace shell is a dipper or bucket 11, across the top of which is a yoke 12 provided with a screw 13. Beneath the yoke, and between it and the upper edge of the bucket is an adjustable lid or top 14 held against a packing 15 in the upper edge of the bucket by means of the screw 13; whereby the opening 16, Fig. 8, may be adjusted, in order to take up more or less water during the rotation of the kiln. Any other suitable construction of adjustable lid may be used.

In the path of rotation of the dipper or bucket 11 and beneath the kiln, is a water tank 25 into which the bucket dips as it rotates with the kiln, and thus dips up a volume of water controlled by the size of opening 16 in its top, Fig. 8. The tank 25 is provided with a water inlet 26 and a water outlet near its top, thereby increasing the maintenance of the level of the water in the tank.

A pipe 17 leads from the bottom of the bucket to the lower inlet end of a section or plate 6, the other end of which is connected by pipe 17 to the next adjacent section or plate 6, if a number of such be used, the last one of the series being provided with a steam blow-off pipe 18 controlled by a suitable hand valve 19. In said pipe 17 connecting the bucket or dipper 11 and the first cooler section 6, I provide a non-return valve 20, of any suitable construction, so that when steam is formed in the coolers, the back pressure will close this valve and prevent the water in the bucket or dipper 11 from being blown out.

In the modified form of construction of plate shown in Fig. 6, I provide a frame 21 arranged to be secured to the shell 1 of the

kiln and extending within the shell a distance equal about to the thickness of the lining L. This frame 21 is provided with a flange 22, whereby it is riveted or otherwise secured to the shell 1 of the kiln, preferably against the inside surface thereof. Distanted somewhat from this flange 22 is a second flange 23, outside of the kiln, and through which bolts 24 pass for securing the plate 6 in the frame. By this means I am enabled by simply removing the securing bolts 24 to remove a worn out plate and insert another without destroying the lining of the kiln.

In Fig. 7 I have shown the dipper or bucket 11 arranged at the upper end of the kiln and connected by pipe 17^a to the lowermost cooler 6, thereby providing a slightly greater head of water at the entrance end of the lowermost cooler. In said Fig. 7, in order to prevent steam from the first plate 6 from entering the water supply pipe 17^a, I may place the non-return valve near the entrance to said plate, or use an additional non-return valve, as indicated at 28.

As many of these sections or plates may be connected together as is found desirable or may be required by the particular size of the kiln used.

The operation is as follows:

As the kiln rotates, usually in a counter-clockwise direction, the bucket or dipper 11 dips into the tank 25, in which the water is kept at a fixed level by reason of the location of the outlet pipe 27 or otherwise. The bucket 11 takes up, through the opening 16 (Fig. 8,) in the top of the bucket and on the side facing the kiln, a quantity of water controlled by the size of this opening. This water flows through the check valve 20, pipe 17, to the plate or plates 6. As the kiln rotates this water comes into contact with the hot face of the plate or plates adjacent the accretions and is converted into steam.

When the head of water on the first cooler exceeds the back pressure of the steam in the system of plates check valve 20 opens and allows the water from the bucket 11 to flow into the plate. The steam pressure set up in the plates is sufficient to cause the check valve 20 in the supply pipe to close, thereby causing the steam to pass through the entire system of coolers and escape through the discharge pipe 18 into the atmosphere.

On the succeeding revolution of the kiln the amount of water entering the plate or plates depends upon the percentage of the evaporation of the water received during the preceding revolution. If the evaporation has been practically completed by the time the plates return to their receiving position, the entire charge of water from the bucket 11 will pass through the check valve 20 into the plates. If the evaporation has not been completed when the coolers reach

their receiving position, only a portion of the water from the bucket 11 will be admitted to the first plate 6, and the balance will be discharged through the opening 16 when 5 the bucket 11 passes the uppermost point in its course.

In other words, the amount of water entering the plate from the bucket is automatically controlled by the steam pressure 10 in the system. The amount of water taken up by the bucket 11 is regulated by adjusting the cover 14 so as to increase or diminish the size of the inlet opening 16. The rate of discharge of the bucket is naturally 15 dependent upon the rate of discharge of the steam from the system, and this can be regulated by means of a valve 19.

It will therefore be seen that the steam is practically all generated in the first or lowest 20 plate 6, and is conducted from this plate to those connected to it, and finally passes into the atmosphere, thus producing a cooling effect sufficient to crack the accretion ring and cause it to fall from the lining.

25 I claim:—

1. The combination with a rotating kiln and a body of water below the same, of a bucket secured to the kiln arranged to pass through said body of water and dip up a 30 quantity thereof during a rotation of the kiln, a hollow cooling section or plate on the kiln, means to supply water from said bucket to said section and a steam exit in the section.

35 2. The combination with a rotating kiln and a body of water below the same; of a bucket secured to the kiln and arranged to pass through said body of water and dip up a quantity thereof during a rotation, a 40 hollow cooling section on the kiln, means to supply water from said bucket to said section, a steam exit in said section and means to prevent steam from passing to the bucket.

3. The combination with a rotating kiln 45 and a body of water below the same; of a bucket secured to the kiln and arranged to pass through said body of water and dip up a quantity thereof during a rotation, a hollow cooling section on the kiln, means to supply water from said bucket to said section, a steam exit in said section, means to prevent steam from passing to the bucket and means to regulate the passage of steam from said section.

50 55 4. In a rotary kiln, the combination with the kiln shell having an opening therein; of a frame secured to said shell within the opening, and a removable cooling section mount-

ed in the frame and having inlet and exhaust connections.

5. The combination with a rotary kiln, of a frame secured in the wall thereof and having two flanges, one of which is secured to the kiln, a removable cooling section mounted in the frame and having flanges co-operating with the other flange of said frame, means to detachably connect said other flange and the section flange, and inlet and outlet means for said section.

6. The combination with a rotary kiln 70 and a body of water beneath the kiln; of means to maintain a constant level of said body of water, means on the kiln and rotating therewith to dip up a quantity of water from said body of water, a hollow cooling 75 section in the wall of the kiln and connected to said dipping means and steam outlet means for said section.

7. The combination with an inclined rotating kiln and a body of water beneath the 80 same near its upper end, means on the kiln to dip up a volume of water from said body as the kiln rotates, a cooling section in the kiln walls near the lower end, a pipe connecting said dipping means with the lower 85 end of said section and a steam exit for said section near its upper end.

8. The combination with an inclined rotating kiln and a body of water beneath the same near its upper end, means on the kiln 90 to dip up a volume of water from said body as the kiln rotates, a cooling section in the kiln walls near the lower end, a pipe connecting said dipping means with the lower end of said section, a non-return valve in 95 said pipe, and a steam exit for said section near its upper end.

9. The combination with a rotating kiln; of a hollow cooling section or plate thereon provided with water-inlet means and means 100 to discharge steam, and means to automatically and periodically supply water to said inlet means.

10. The combination with a rotatable kiln; of a hollow cooling section or plate thereon 105 provided with water inlet means and suitable outlet means on the kiln for delivering to said inlet means a quantity of water at each rotation.

In testimony that I claim the foregoing as 110 my invention, I have signed my name in presence of two subscribing witnesses.
